UNITED STATES PATENT OFFICE.

MICHAEL HOLROYD SMITH, OF LONDON, ENGLAND.

WHEEL.

SPECIFICATION forming part of Letters Patent No. 606,365, dated June 28, 1898.

Application filed June 29, 1897. Serial No. 642,889. (No model.)

To all whom it may concern:

Be it known that I, MICHAEL HOLROYD SMITH, a subject of the Queen of Great Britain and Ireland, and a resident of Albany 5 Buildings, 47 Victoria street, Westminster, London, in the county of Middlesex, England, have invented certain new and useful Improvements in Wheels, of which the following is a specification.

10 The object of my invention is an improved arrangement of parts forming a flexible or spring hub which will absorb shocks transmitted from the rim of the wheel.

The invention is based on the principle that 15 the axis must be free to move radially, but be restrained from twisting, the radial movement being restrained by springs. In many previous inventions where springs have been introduced they have been subject not only 20 to compression and extension, but have also had to stand a lateral strain. In others the lateral strain has been obviated, but by employment of complicated mechanism, such as sliding devices placed at right angles. This 25 invention presents a simple solution of the problem.

It is a well-known law of mechanics that a circular movement is a compound of two movements at right angles to one another. Recognizing this law, I take advantage of the 30 parallel movement employed by Watts for beam-engines and make a combination of two such movements, attaching the outer ends of one set of levers to a ring or frame, which 35 may be the rim of the wheel, or preferably a ring situated between the rim and the center, forming what may be described as an "enlarged hub," the other ends of the first set of levers being attached to an inner ring or 40 frame which corresponds with and has the same function as the link in Watts's parallel movement, the center of which is attached to the end of the piston-rod. Between this frame and the outer ring or enlarged hub I 45 place springs or elastic media which control its movement. It is obvious that the frame can only move in a direction at right angles to the normal position of the levers. To this inner frame I attach the outer ends of another 50 set of levers so that their normal position is at right angles with the first set, attached to the enlarged hub. The inner ends of this

second set of levers are linked together by what forms the wheel-center, into which the axle may be keyed or run freely, as circumstances may require. It is obvious that the movement of the center in relation to the inner frame can only be at right angles to the normal position of its attached levers, and its movement is controlled by springs or the like 55 placed between the center and the inner frame. The movement of the center therefore is at right angles to the movement of the inner frame, and the combined movement of the center and the inner frame at right angles to one another permits a radial movement of the center in relation to the outer ring or enlarged hub; also, the combined action of the first and second set of levers prevents any torsional movement of the center. 60

The outer ring or enlarged hub is preferably made circular. The inner frame may also be circular, but preferably rectangular; but both inner frame and enlarged hub may be of polygon form or modifications thereof, as 75 may be best suitable for allowing the required movement and providing seats or attachments for the springs. The minimum number of springs employed would be four; but they may be multiplied in pairs or groups, as 80 circumstances may require.

Referring to the drawings, which form a part of this specification, Figure 1 is a diagrammatic view of a hub to illustrate the principle of my invention. Fig. 1^a is a diagrammatic view of the arrangement applied to a wheel. Fig. 2 is an elevation of one form of hub. Fig. 3 is a plan of same. Fig. 4 is an elevation of another form of hub. Fig. 5 is a plan of same.

Referring first to Fig. 1, *a* represents the outer ring or frame, which in this case is situated between the rim of the wheel and the center *b*, such ring or frame being pivotally connected by levers *c c'* to an inner ring or frame *d*. At the point where these levers are pivoted to the inner frame are pivotally attached the outer ends of levers *e e'*, the inner ends of which are pivoted to a link *f*, which virtually forms or is attached to the wheel-center and in which the axle or shaft is keyed or in which it rotates, as required. The dotted lines in this figure show the position the inner frame and connected parts occupy in

relation to a point of the rim immediately below same when a weight is carried by the axle, a compound of this movement (or a similar movement in the opposite direction) 5 with a movement of the inner frame at right angles thereto providing the radial movement of the inner frame. The springs for controlling these movements and affording the cushioning action are not indicated in this diagram, 10 but are shown in Figs. 2 and 3, which illustrate a form where a narrow hub is desired, and in which it will be seen that the outer ring or enlarged hub is composed of two rings *a a*, connected and spaced apart by posts *g g'*, on which 15 are pivoted the levers *c c* and *c' c'*, respectively, each pair of levers being bent at their inner ends in order that they may be united by pivoting to the inner frame and curved outwardly to permit the movement of the link 20 *f*, said inner frame in this case departing from the ring form and taking the form of the two slotted and shaped plates *d d*. To the plates forming this frame are pivoted the four levers *eee' e'*, which are further connected with each 25 other by the plates or links *ff*. These plates or links *f* carry suitable bearings, if desired, for the shaft or axle *b*, and attached to or forming part of them and capable of moving within the frame *d* is a block *h*, carrying cups 30 or spring-seats *i i*, while the outer ends of the plates *d d* carry cups or spring-seats *j j*. Between these are the springs *k k*, which are compressed with the movement of the block *h* and connected parts against them. The frame 35 *d* also carries cups or spring-seats *i' i'*, and the outer rings *a* or frame the cups or spring-seats *j' j'*, the latter being carried by plates *j*, Fig. 3, which assist in connecting the rings *a a*, forming the enlarged hub. Between these 40 cups or spring-seats *i' j'* are the springs *k'*, which are compressed with the movement of the inner frame against them. The spokes are attached to the rings *a a*, forming the enlarged hub, and connect it with the usual rim.

It will be seen that the levers effect the driving of the wheel and take up the torsional movement or twist, while the links *ff* assist to resist the lateral stress and keep the axle at right angles to the wheel. 45

In Figs. 4 and 5 is shown an arrangement 50 where a wider hub is required, and in this case the springs *k* and *k'* are doubled and placed outside of the frame *d*, the studs for carrying same being also duplicated and being suitably carried. A single link or center 55 *f* is employed in place of a pair, such link being carried centrally by the block *h* or central hub.

Having now described my invention, what I claim as new, and desire to secure by Letters 60 Patent, is—

1. In a wheel, a slotted hub, an axle passing therethrough, springs applied to opposite sides of the hub in a line therewith, and springs applied between the outer side of the hub and the inner sides of the wheel, and a lever secured to the axle, combined with a series of pivoted levers placed upon opposite sides of the hub, the outer one of each series of levers having its outer end pivoted to the wheel, substantially as shown. 70

2. In a wheel, a slotted hub, the axle passing therethrough, and springs placed in opposite ends of the slot in the hub, and having their inner ends to bear against opposite sides 75 of the axle, combined with a lever connected to the axle, and a series of levers connected to each end of the lever secured to the axle, the outer end of each one of each series being connected to the rim; and springs placed 80 between the hub and the rim of the wheel, substantially as specified.

In witness whereof I have hereunto set my hand in presence of two witnesses.

MICHAEL HOLROYD SMITH.
